Specification of Letters Patent.

Patented July 6, 1915.

Application filed November 12, 1912. Serial No. 731,023.

To all whom it may concern:

Be it known that I, NÁNDOR KOLÁR, manager, a subject of the King of Hungary, residing at Budapest, in the Kingdom of Hungary, have invented new and useful Improvements in Calculating and Printing Apparatus for Meters; and I do hereby declare the following to be a full, clear, and exact description of the same.

10 The present invention relates to apparatus for calculating and printing the corresponding monetary values from the counting trains of gas, electric, and like consumption meters and has for its object to insure both reliability and durability and to prevent abuse while providing a construction of the most simple kind.

15 In the accompanying drawings two examples in construction of the calculating and printing apparatus are illustrated, the first being suitable for a gas meter and the second for an electric meter.

Figure 1 is a front view of the apparatus suitable for a gas meter with the casing in longitudinal section. Fig. 2 is a plan. Fig. 3 is a cross-section on the line 3-3, and Fig. 4 is a cross-section on the line 4-4 of Fig. 1. Fig. 5 shows the account or monetary value printed. Fig. 6 is a front view 20 of the apparatus for electric meters. Fig. 7 is a detail view, and Fig. 8 a diagram of the electrical connections. Figs. 9 and 10 show respectively in front elevation and cross-section on the line 10-10 of Fig. 9 a modified construction of the cost printing and indicating train. Figs. 11 and 12 are respectively side and front views of the frame serving for the insertion of the account form. Fig. 13 shows in section on the line 13-13 of Fig. 14 the safety device serving to prevent abuse. Fig. 14 is a front view of the safety device shown in Fig. 13. Fig. 15 illustrates one mode of connecting the calculating and printing apparatus with the counting train of a gas meter. Fig. 16 illustrates a connection between the calculating and printing apparatus and a gas meter when considerable distance intervenes, and Fig. 17 shows as an example one form 50 of key for manipulating the printing apparatus being partly in section with the counting train in elevation.

Referring to Figs. 1-5 of the accompany-

ing drawings 1, 2, 3 are the spindles of the indicator of the usual counting train E of 55 a gas meter to which motion is transmitted in a known manner by a screwed spindle 4. By means of bevel wheels 5, 6, the screwed spindle 4 drives a counting train F which consists of numbering disks 8, 9, 10 advanced step by step and of a transfer disk 7 connected with the bevel wheel 6. The counting train F may be *per se* of any desired well known construction and is so devised that upon one revolution of the transfer disk 7 the numbering disk 8 is advanced by one number while the numbering disks 9 and 10 are each advanced by a single number upon a complete revolution of the disks 8 and 9 respectively. The forward movement of the disks after a complete revolution of the adjacent disk is effected in a known manner by the transfer wheels 11. The transfer wheels 11 as well as the disks 7, 8, 9 and 10 are mounted freely upon their 65 spindles. The diameters of the bevel wheels 5, 6 and of the transfer disk 7 are so proportioned that the counting train F always shows the amount in marks and pfennigs and corresponding to the consumption of gas 80 indicated by the counting train E. Upon a change in the rate the calculating and printing apparatus can be adjusted to the current rate by changing the wheels 5, 6, or when a bevel wheel of sufficient width of 85 tooth is employed by changing one of the bevel wheels. In case the price per unit of gas is not a fractional part of a mark, then instead of a single numbering disk 8 for indicating the pfennigs two such numbering 90 disks must be provided. The bosses of the numbering disks carry or are formed as heart-shaped cams 12 (see Fig. 4) with which resetting-levers 14 keyed upon a spindle 13 can engage. The spindle 13 carries 95 two further levers 15, 15 with the hook-shaped ends (see Fig. 3) on which rest the ends of the spindle 16 which carries the transfer wheels 11. The ends of the spindle 16 also pass through inclined slots 17 formed in the end walls of the framework. The numbering disks 8, 9, 10 are formed also as printing disks for which the plate 19 serves as a platen. In order that the numbering disk spindle during printing should not be 100 injuriously affected a counter-pressure bear-

ing plate 20 is provided and arranged parallel to the platen 19. A parallel movement is provided for the platen 19 and bearing plate 20 by guide pins 21. Within the framework of the apparatus there are mounted upon spindles 22, 22 two eccentrics 23, the rods of which are pivotally connected, on the one hand with the platen 19 and on the other hand with the bearing plate 20. The spindles 22 are mounted in elongated bearings 22' and can be rotated by means of the toothed wheels 24 from the spindle 25. Upon the spindle 25 is mounted a ratchet wheel 26 with which engages a pawl 27 permitting rotation of the spindle 25 in one direction only. Further a finger 28 is mounted upon the spindle 25 and adapted to engage with a surface 29 upon one of the resetting levers 14. One end of the spindle 25 is squared opposite which end the casing 31 is provided with a key-hole 32 through which a key 33 can be passed. The wards 34 of the key and the form of the key-hole insure that the key can be inserted and withdrawn in a given position only. The casing 31 is provided with a slot 35 through which a sheet 36 of paper can be passed into the apparatus in such a manner as to rest against the platen 19.

30 The operation is as follows:—The sheet of paper 36 is pushed through the slot 35 in the casing until its lower edge strikes a supporting stop 37 formed at the lower end of the platen 19. The key 33 is pushed 35 through the key-hole 32 in the casing and over the squared spindle end 30. On turning the key the spindle 25 is rotated in the direction of the arrow 38 (Fig. 4). The spindle 25 by means of the spur wheels 24 causes the spindles 22 to rotate which in their turn by means of the eccentrics 23 cause the plates 19 and 20 to approach one another, the guide pins 21 insuring a parallel movement of the two plates. By these 40 means the sheet of paper 36 and the platen 19 are on the one hand pressed against the numbering disks 8, 9, 10 of the counting train F whereby the state of the counting train F is printed off at the spot A on the sheet 36 of paper (Fig. 5) while on the other hand the plate 20 is pressed against the numbering disks 8, 9, 10 at a diametrically opposite point so as to act as a counter-bearing during printing and thus prevent 45 the numbering disk spindle from being injuriously affected during the operation of printing. The elongated bearings 22' permit of a slight lateral movement of the spindles 22 so that equalization of pressure on 50 the two sides of the numbering disks is insured. Printing is effected by means of a carbon paper inserted at the same time with the sheet 36. The printing operation is completed after the spindle 25 has been rotated 55 through 180°. Thereupon the two plates 19, 20 move away from each other and the finger 28 on the spindle 25 engages with the nose 29 on the lever 14 so that the spindle 13 together with the two levers 15 are caused to rotate in the direction of the arrow 40 (Fig. 3). As a result of the combined effect of the slot 17 and the inner edge of the levers 15 upon which the spindle 16 rests, the spindle 16 with the transfer wheels 11 is raised so that the numbering disks 8, 70 9, 10 are released. The lever 14 is now pressed farther inward by the finger 28 so that the free ends of the resetting levers 14 after the release of the numbering disks 8, 75 9, 10 engage the heart-shaped cams 12 and exert a pressure upon them sufficient to return, in a manner known *per se*, the heart-shaped cams 12, together with the numbering disks connected therewith, to zero position. When the key 33 and the spindle 25 are turned farther, the finger 28 releases the lever 14 so that the spindle 13 returns under the influence of the spring 39 to its original position, which is determined by the engagement of a projection on the lever 15 with the spindle 25 whereby the wheels 11 are again caused to engage with the numbering disks and the levers 14 removed from the heart-shaped cams 12. When the key 33 and spindle 25 has been rotated through 360° 80 the key can be removed through the key-hole and the apparatus is then in the original condition. The sheet of paper 36 can now be withdrawn. Upon this sheet has been printed the amount payable for consumption since the payment last due while the counting train F indicating this amount has been restored to zero position. Two account sheets 36 may simultaneously be inserted in the apparatus of which one may 85 serve as an account and receipt for filing by the consumer while the other sheet may be kept as a record for the distributing department. The ratchet wheel 26 and pawl 27 prevent the key from being turned in the wrong direction and from being withdrawn before the printing operation has been completed and the counting train F returned to zero position. On the pointers themselves, or on special arms on the indicator spindles 1, 2, 3 of the counting train E giving the condition of the meter, needles 41 are arranged which, upon the application of pressure prick holes 45 (Fig. 5) in the sheet 36 of paper and reproduce the state 90 of the meter, at the moment of printing, upon the dials 42 on the sheet 36 of paper. A guide slot 43 is provided in the framework for the reception of type 44 for giving the number of the meter and, or in lieu thereof, the number of the consumer so that as the state of the counting train is printed off the meter number and the consumer's number can be simultaneously printed upon the account sheet. After printing, the ac- 95 100 105 110 115 120 125 130

count sheet appears as shown in Fig. 5, the common letter press being omitted in this figure. The amount payable for consumption since the payment last due is shown at A, the meter number at B, the consumer's number at C and at D the state of the meter is shown by the perforations 45 on the dials 42 previously printed on the account sheet.

In the calculating and printing apparatus applicable to an electric meter and illustrated in Figs. 6-8, a separate transfer magnet 46 serves for advancing the printing counting train so that, the calculating and printing apparatus may not throw any load upon the electric meter. Upon consumption of a unit the meter closes a circuit to energize the transfer magnet 46 which by the attraction of its armature advances one or more elements of the calculating train to accord with the unit consumed. The electrical connections of the transfer magnet 46 of the calculating and printing apparatus is illustrated in Fig. 8, M being the electric meter. The transfer magnet 46 is in shunt across the mains 47, 47 of the distributing circuit and in series with a rotary circuit breaker 48 provided with sliding brushes 49. The circuit-breaker 48 is provided with a rapid intermittent motion and at each revolution energizes once the magnet 46. The mechanism which serves to rotate the circuit-breaker 48 is shown at K, Fig. 6, in front elevation and in Fig. 7 in plan. Upon the spindle 50 of the unit wheel of the counting train of the meter is freely mounted an insulating and contact drum 48 provided with contact segments 51. The drum 48 is connected to the spindle 50 by a spring 52 and in such a manner that when the drum is held up by the pin 53 and pawl 54 the spindle 50 rotating in the direction of the arrow 55 places the spring 52 under tension. The pawl 54 is pivoted upon a pin 56 and rigidly connected with a lever 57 while a finger 58 keyed fast on the spindle 50 is adapted to coöperate with the lever 57. When the spindle 50 putting the spring 52 under tension has completed a revolution the finger 58 presses the lever 57 outward so that the pawl 54 releases the pin 53 and the drum 48 under the influence of the tension on the spring 52 makes in a moment a complete revolution when it is stopped by an arm 59 mounting the spindle striking the pin 53. During the revolution of the drum 48 the current circuit of the magnet 46 is closed by the brushes 49 and contact segment 51 so that its armature 60 is attracted. The armature 60 carries a toothed segment 61 which, when the armature is attracted, rotates a spur wheel 62 through a given angle. This spur wheel transmits its motion by means of a pawl 63 to a ratchet wheel 64 with which a bevel wheel 65 is connected. This bevel

wheel 65 engages with a bevel wheel 66 which drives the counting train of the calculating and printing apparatus. It would suffice if the calculating and printing apparatus comprised a single counting train F 70 driven by gear wheels 67, 68, 69 and 70 and adapted to indicate the amount payable according to the current consumption. In the example illustrated in Fig. 6, however, two additional counting trains G and H are provided as printing mechanism, the counting train G being directly driven by the spindle of the bevel wheel 66 and the counting train H being driven through the gear wheels 67, 68, 71. The counting train G 80 shows the current state of the meter while the counting train H shows the amount of electricity consumed since the last payment and must accordingly be returned, after the printing operation as well as the counting 85 train F giving the amount payable to zero position. Both the counting trains F and H are precisely the same as the counting train F shown in Figs. 1-4. The remaining parts of the apparatus are likewise essentially the 90 same as the corresponding parts in the constructional form described with reference to Figs. 1-4. On printing, the state of all three counting trains as well as both numbers B and C are printed off whereupon 95 both counting trains F and H are automatically returned to zero position. When the price of a unit is altered the wheels 69 and 70 are for example changed so that the motion transmitted to the counting train F always corresponds to the current unit rate. 100

As already explained, on resetting the mechanism for indicating the monetary value the transfer wheels 11 are withdrawn from the teeth of the numbering disks. In order to hold the transfer wheels in position during the time they are out of engagement with the numbering disks there is provided as shown in Figs. 9 and 10 a guiding device which holds the transfer wheels 11 fast in the position in which they were in before the disengagement. This guide as shown in Figs. 9 and 10 consists of two wires which are stretched across the frame 115 parallel to each other and in such a manner that one tooth on the transfer wheels 11 enters between the two wires 94 before the transfer wheels pass out of engagement with the numbering disks. Figs. 9 and 10 further show a device of simple construction whereby the counting train can be adjusted to correspond with different unit rates, the first numbering disk 95 which indicates the smallest monetary unit always receiving a rapid motion by steps. The essential feature of this device resides herein that in front of the first numbering disk 95 and coupled therewith by means of a transfer wheel 11, there is mounted a loose disk 96 which is provided with a number of transfer 120

teeth 97 corresponding to the unit rate and which is coupled with the driving wheel 6 or with the driving spindle of the counting train by means of a spring 98, which is subjected to tension when the driving spindle is rotated while the loose disk 96 is held up by a catch released at each revolution of the driving wheel or spindle. The catch consists as shown in Figs. 9 and 10 of a pawl 100 provided with a shoulder 101 which arrests the pin 102 on the disk 96. When the driving wheel 6 rotates in the direction of the arrow 105 the spring 98, which is secured on the one hand to the disk 96 and on the other hand to the boss 104, is placed under tension while the pin 102 is pressed against the shoulder 101 on the pawl 100. A nose 103 on the boss 104 of the driving wheel 6 at each revolution 15 presses back the pawl 100 so that the pin 102 slides off the shoulder 101 and the disk 96 under the influence of the tension on the spring 98 makes a complete revolution during which the teeth 97 on the transfer disk 96 by means of the transfer wheel 11 advances the first numbering disk 95 by as many units as the transfer disk 96 has teeth. When the unit rate is altered all that is required is a change in the transfer disk 96.

In order to facilitate the insertion and printing off of the account a frame may conveniently be employed consisting of two portions pivoted together at 72 and adapted to snap together of which one portion forming the rear wall 73 is solid with the exception of openings 75 corresponding with the dials 42 (Fig. 5) while the other portion forming the front wall 74 consists of a narrow frame adapted to hold down the edges of the account form when inserted between the two portions. The frame being opened the account form is placed between the two portions 73, 74, whereupon the two portions of the frame are snapped together.

When the account is to be printed the frame is inserted in the slot 85 (Fig. 3) of the apparatus so that the frame portion 74 faces the printing mechanism. To avoid misuse a catch may be employed adapted to stop rotation of the spindle 25 before the printing operation can be effected and which can only be released when the proper key has been inserted. One form of construction of such a safety device is shown in Figs. 13 and 14, as an example. In these figures there is shown at the same time a closure for the slot 35 (Fig. 3) for the insertion of the account form. On the spindle 25 there is mounted a ratchet wheel 76 with which the pawl 77 engages so that the spindle can be turned by means of the key in one direction only. On the front end of the spindle 25 is mounted a disk 78 which is provided with a tooth 79 and which is arrested after rotation through a small angle by a pawl 80

engaging with the tooth 79. Upon the disk 78 is mounted a sleeve 81 adapted to receive the wards of the key and arranged to extend to the wall of the casing 31 so as to shut off all passage through the key-hole 70 to the interior of the apparatus. The sleeve is open at the side 82. Beneath the spindle 25 several holding levers 84 are arranged so as to rotate about a pivot pin 83 and provided with slots 86 or tongue of the pawl 80 bent at right angles. The holding levers prevent vibration of the pawl 80. The slot 85 is closed by a flap 87 pivoted to the casing 31 and connected to the pawl 80 by a rod 88. The spindle 25 carries two segments 89 adapted to engage noses 90 on the flap 87 so that the flap is firmly held in the closed position.

The mode of operation is as follows:— The position of rest of the various parts is as shown in Fig. 13, the position of the key-hole corresponding with the position of the sleeve 81. The key after insertion through the key-hole 32 into the sleeve 81 can be 90 turned in the direction of the arrow 106 (Fig. 13) carrying with it the sleeve 81 and spindle 25. During this movement the wards of the key operate on the portions 91 of the holding levers 84 so that the latter 95 by means of the appropriate key are severally pressed down to such an extent that the slot 92 of each holding lever is located opposite the tongue 86 on the pawl 80. Simultaneously the tooth 79 on the disk 78 strikes 100 the pawl 80 so that the key cannot be turned farther. At this moment the segments 89 have been turned sufficiently far to release the noses 90 on the flap 87. Pressure is now applied to the flap 87 by means of the frame 105 73, 74, holding the account form, so as to open the flap and also by means of the connecting rod 88 to press the pawl 80 back out of the path of the tooth 79 and thus release the disk 78. The frame 73, 74 can now be 110 pushed into the apparatus, the spindle 25 rotated further by means of the key and the printing of the account accomplished. Should a false key be inserted the holding levers 84 would not take up such a position as to permit of the yielding of the pawl 80 so that neither could the flap 87 be depressed nor the disk 78 released. The key 115 cannot therefore be turned farther around and the backward turning of the key is prevented by the ratchet wheel 76. As the key has been already turned so far that the wards are no longer opposite the key-hole 32 the key cannot be removed and is held fast in the apparatus so that it may lead to 120 the identification of the operator. After printing, the frame 73, 74 is removed from the apparatus whereupon the spring 93 returns the pawl 80 to its position of rest thus closing the flap 87. After turning the key 125 130

through 360° it can be withdrawn. Mean-
while the segments 89 have secured the
flap 87.

When the calculating and printing apparatus is to be applied on the spot to an existing gas meter, so as to avoid unnecessary alteration the arrangement shown in Fig. 15 may be conveniently adopted. A hole 109 is cut in the casing 108 of the counting train above the liter indicating drum 107 through which hole a flexible shaft 110 is passed into the casing 108. The lower end of the flexible shaft is coupled in any desired and suitable manner with the drum 107 while the upper end of the flexible shaft is connected by the collar 111 and screw 112 with the gear wheel 5 which drives the counting train of the calculating and printing apparatus. The employment of a flexible shaft 110 between the liter drum 107 and the driving wheel 5 permits of the gas meter G (Fig. 16) being located at a considerable distance from the calculating and printing apparatus by providing a corresponding length of flexible shaft within a tube 113.

In order to avoid, or render evident, misuse of the key intended for operating the calculating and printing apparatus, the key is provided with a counting train adapted to register each use of the key. Fig. 17 shows as an example one mode of constructing such a key. As shown in Fig. 17 a pin 116 connected with a pawl 117 is located within the shaft 114 of the key so as to be capable of axial movement against the influence of a spring 115. Each time the key is inserted through the key-hole 32 (Fig. 14) the end 30 of the spindle 25 presses the pin 116 of the key inward whereby the pawl 117 advances the unit wheel 118 of the counting train by one unit. The "tens" and "hundreds" wheels 119 and 120 respectively of the counting train are advanced, after one revolution each, by one step in a known manner by the units and "tens" wheels respectively. Locking pawls (not shown) prevent backward movement of the numbering wheels. Obviously the counting train can be furnished with more than three numbering wheels.

What I claim and desire to secure by Letters Patent, is:—

1. In a calculating and printing apparatus, the combination of a plurality of numbering disks; a platen adapted to engage one part of the periphery of the disks; a counter bearing adapted to engage the diametrically opposite part of said periphery; and means for causing relative motion between said platen and counter bearing.

2. In a printing apparatus, the combination of a printing disk; a platen adapted to engage a point on the periphery of the disk; a counter bearing adapted to engage a substantially diametrically opposite point

of said periphery; and means for causing relative motion between said platen and counter bearing.

3. In a calculating and printing apparatus, the combination of a counting train having numbering disks having intermittent movement; means by which printing may be effected at a part of the disks; and a counter bearing; and means for pressing the counter bearing against the periphery of the disks diametrically opposite to said part.

4. In a calculating and printing apparatus, the combination of a plurality of numbering disks; a platen adapted to be moved toward the periphery of the disks at one part; a counter bearing adapted to be pushed against the disk at a part diametrically opposite to the first named part; a yieldably mounted spindle; eccentrics secured thereon at different angles; and means connecting the counter bearing and platen to the eccentrics.

5. In a calculating and printing apparatus, the combination of a plurality of numbering disks; a platen adapted to be moved toward the periphery of the disks at one part; a counter bearing adapted to be pushed against the disk at a part diametrically opposite to the first named part; a yieldably mounted spindle; eccentrics secured thereon at substantially 180° apart, and means connecting the eccentrics to the counter bearing and platen.

6. In a calculating and printing apparatus, the combination of printing disks; a device coöperating therewith for effecting the printing; means operated by a key for operating said device for effecting the printing and for resetting the disks to zero; a part rotatable in one direction only by the key; a catch adapted to hold said part against movement after the key has been turned far enough to prevent its withdrawal; and means for preventing the release of said catch and permitting its release when engaged by the wards of a proper key.

7. In a calculating and printing apparatus, the combination of printing disks; a device coöperating therewith for effecting the printing; means operated by a key for operating said device for effecting the printing and for resetting the disks to zero; a part rotatable in one direction only by the key; a catch adapted to hold said part against movement after the key has been turned far enough to prevent its withdrawal; means for preventing the release of said catch and permitting its release when engaged by the wards of a proper key; means for holding the account to be printed; a closure for said means; and an operative connection between said closure and said catch.

8. In a calculating and printing apparatus, the combination of a printing device; means operated by a key for effecting the printing; means for limiting the movement of the key after a partial rotation; means normally preventing release of the limiting means and adapted, when engaged by a proper key, to permit the release of the limiting means; and means operated by the insertion of the account to be printed from to cause the limiting means to release the key.
9. In a calculating apparatus, the combination of a train of numbering disks; a loose transfer disk provided with a number of transfer teeth equal to the rate unit; a transfer wheel connecting the transfer

disk with the numbering disk of the smallest denomination; a driving spindle; a spring connecting the driving spring with the transfer disk and pressing the transfer disk forwardly; a catch normally holding the transfer disk against forward movement; and means operatively connected to the driving spindle for releasing the catch on each revolution of the driving spindle.

In testimony whereof, I have signed my name to this specification in the presence of two subscribing witnesses.
